SCAFFOLDING FOR DOME STRUCTURES

John P. Reinhardt, Syosset, N.Y., assignor, by mesne assignments, to Baker-Roos, Inc., Indianapolis, Ind., a corporation of Indiana

Filed June 28, 1961, Ser. No. 120,234
8 Claims. (Cl. 182—12)

This invention relates to scaffolding for dome structures.

An object of this invention is to provide scaffolding for the outer surface of a part spherical structure provided with means to move the scaffolding all around the structure about its vertical axis, so that workmen on the scaffolding may paint or otherwise service said outer surface.

A further object of this invention is to provide scaffolding of the character described comprising a plurality of step-ladders interconnected in tandem and hung from cables extending to the upper end of the axis of the structure, each ladder resting on the outer surface of said structure and being provided with steps, the steps of each ladder being substantially horizontal to facilitate climbing up the ladders.

Yet a further object of this invention is to provide in scaffolding of the character described, a hanging scaffold suspended from the lower end of the lowermost ladder, winch means being provided on said hanging scaffold to raise the same to desired height.

Yet a further object of this invention is to provide in scaffolding of the character described, scaffold ladders each provided with individual motorized rollers to move the ladders sideways around the structure, the motive mechanism for the ladders being so selected that the ladders can move at relative speed which will carry the scaffolding around the structure with the ladders remaining in line.

A still further object of this invention is to provide, in scaffolding of the character described, removable means to keep the motorized rollers off the surface of the dome, to facilitate pulling the scaffolding up to the proper position relative to the top of the dome, and whereby upon removal of said means, the rollers will contact the outer surface of the dome.

Yet another object of this invention is to provide a strong, rugged and durable scaffolding of the character described which shall be relatively inexpensive to manufacture, easy to operate and yet practical and efficient to a high degree in use.

Other objects of this invention will in part be obvious and in part hereinafter pointed out.

The invention accordingly consists in the features of construction, combination of elements, and arrangement of parts, which shall be exemplified in the construction hereinafter described, and of which the scope of invention will be indicated in the following claims.

In the accompanying drawings in which is shown various illustrative embodiments of this invention,

FIG. 1 is an outer view of a dome structure provided with scaffolding embodying the invention;

FIG. 2 is an elevational view of the hanging scaffold;

FIG. 3 is a cross-sectional view taken on line 3—3 of FIG. 2;

FIG. 3a is a cross-sectional view taken on line 3a—3a of FIG. 2;

FIG. 4 is a partial, enlarged, cross-sectional view taken on line 4—4 of FIG. 3;

FIG. 5 is a top view of the lowermost ladder and part of the one thereabove;

FIG. 6 is a side elevational view of the structure shown in FIG. 5;

FIG. 6a is a top view of a front corner of a ladder;

FIG. 6b is a cross-sectional view taken on line 6b—6b of FIG. 6a;

2

FIG. 7 is a top view of the upper end of the scaffolding and the top anchor bearing;

FIG. 8 is an enlarged view of the motor drive shown in FIG. 6;

FIG. 9 is an enlarged top view of one of the cable dollies;

FIG. 10 is a cross-sectional view taken on line 10—10 of FIG. 9;

FIG. 11 is a vertical view of the anchor bearing at the top of the dome, with parts broken away and in cross-section; and

FIG. 12 is a cross-sectional view taken on line 12—12 of FIG. 11.

Referring now in detail to the drawing, 10 designates 15 a dome-like structure provided with scaffolding 11 embodying the invention.

The dome structure may comprise a part of a sphere, from below a horizontal plane passing through the center of the sphere, to the top. This structure may be hundreds 20 of feet in diameter. Difficulty has been experienced in painting the outside of the structure or otherwise servicing the same, because of difficulty in getting workmen to all parts of the surface. This structure may be made of steel and may be about one inch in thickness.

25 The structure 10 may be supported by suitable supporting means 12 provided with a door 13.

At the upper end of the vertical axis of the structure 10, is an anchor bearing 14 to be described in detail hereinafter, and carrying a lifting winch 15 for lifting or pulling 30 a pair of parallel cables 16 clamped to over spaced dollies 17. Each dolly 17 comprises spaced pairs of spaced transverse channels 18 interconnected by end channels 18a welded thereto and carrying longitudinal axles 18b on which are mounted rotary rubber lined wheels 35 18c disposed between the pairs of channels and contacting the outer surface of the dome. The cables 16 are fixed to the tops of channel 18 by means of clamps 19.

The upper ends of cables 16 are anchored to the anchor bearing 14 in the manner to be described hereinafter.

40 The cables 16 are connected at their lower ends to the upper end of a scaffold ladder 25 forming one of a series of tandem connected ladders which are of the same construction except as noted hereinafter.

The ladders 25 are interconnected in tandem and lie against the outer surface of the dome structure 10.

45 Each ladder 25 comprises parallel side frames 26 interconnected by steps 27. Each side frame comprises top and bottom parallel pipes 28 interconnected by a plurality of crossing braces 29 between which are cross-bars or pipes 30. Crossing braces 29 are welded to each other and to the pipes 28. Bars or pipes 30 are welded to pipes 28. The steps 27 each comprises a rectangular frame 32 carrying a tread 33 of expanded metal. The steps are inclined to the longitudinal axis of the ladder. The angle of the steps 27 is such that when the scaffolding is in place in the structures the steps of the various ladders are substantially horizontal. Thus the steps of the uppermost ladder 25 are closer to being parallel with the axis of the ladder, and in the lowermost ladder, the steps are closer to being normal to its axis.

50 At the upper end of each ladder is a tongue 35 received between a pair of parallel tongues 36 at the lower end of each ladder. Said tongues are apertured to receive a pivot pin 37 to allow for some swinging movement of one ladder relative to its adjacent ladders.

55 At the front end of each ladder are side plates 40 welded to the side frames 26. Welded to the side frames 40 are vertical sleeves, tubes or pipes 41. Rotatably mounted in each pipe 41 is a rod 41a having a wrench 60 engaging polygonal portion 41b at its upper end. Fixed to each rod 41a below portion 41b, as by set screw 41c,

is a retaining collar 41d contacting the upper end of tube 41. Fixed to the lower end of rod 41a is a castor fork or yoke 41e comprising a top plate 41f from which extend downwardly, ears 41g carrying a transverse shaft 41h on which is mounted a castor wheel 42.

Between the lower end of tube 41 and top plate 41f is a bronze washer 41j.

Top plate 41f is formed with two tapped openings 41k and 41l spaced 90° apart and having equal radii to the axis of sleeve 41. Opening 41k is forward of the axis of sleeve 41, while opening 41l is outwardly of said axis.

Fixed to the lower end of each sleeve 41 is a lug 43 which extends forwardly and is formed with clear hole 43a adapted to selectively register with tapped openings 41k and 41l upon rotating the rod 41a from the position of FIGS. 4, 6, 6a, 6b outwardly through an angle of 90°, to bring the wheels from a position in which the ladders move up or down, to a position in which the ladders move around the vertical axis of the dome.

Slidable in opening 43a of each lug is a bolt 43b which may be screwed into either opening 41k or 41l.

At the rear end of each ladder 25 are brackets 44 connected by chains 45 to brackets 46 at the front ends of adjacent ladders.

Fixed to the rear or lower end of each ladder 25 are brackets 48 having parallel portions 49 and outwardly extending aligned portions 50. Bolted to the outwardly extending portions 50 are jack screw sleeves 51 in which are screwed jacks 51a carrying casters 52. The jacks 51a are adjustable to lift the rear ends of the ladders away from the dome structure 10. The jacks may be removed by unbolting them from brackets 48.

Fixed to one side of the rear end of each ladder 25 is a plate 53. Fixed to opposite sides of the rear end of the ladder are symmetrical brackets 54 of angle shape having longitudinal portions 54a and outwardly extending portions 54b. Mounted on plate 53 is an electric motor 60 coupled by a coupling 61 to a speed reduction gear box 62 from which extends a shaft 63 passing through an opening in wall 54b and carrying a gear 64. Mounted on and between walls 50, 54b is a shaft 66, carrying a bronze bushing 66a on which is rotatably mounted a pneumatic roller 71. Fixed to one end of each roller is an assembly 69 comprising a wheel hub 71a, a sprocket 67 and a gear 65 bolted together by bolts 71b. Gear 65 meshes with gear 64.

A shaft 70 parallel to shaft 66 is mounted on walls 50, 54b at the opposite side of the ladder supporting a similar pneumatic roller 71 provided with a similar assembly 69. A sprocket chain 68 connects the sprocket wheel 67 of one assembly 69 with the sprocket wheel of the other assembly.

These rollers 71 are maintained in spaced relation to the outer surface of dome structure 10 (when the scaffolding is being pulled up by the winch 15 on the anchor bearing 14) by the jacks 51a. However, when it is desired to swing the scaffolding around the dome structure, the jacks may be first adjusted to allow rollers 71 to contact the dome, and then the jack sleeves 51 may be unbolted and removed.

The speed of the motors 60 and their drives may be so adjusted that, as the motors operate, the scaffolding will travel around the dome structure, about its vertical axis, with the ladders 25 substantially in line. The axes of the rollers 71 are parallel to the axes of the ladders so that the ladders will move sideways, being supported at their rear ends on said rollers or tires, and at their front ends on the casters 42.

There is also provided a hanging scaffold 80 suspended from the lower end of the lowermost ladder 25. Said scaffold 80 is in the form of a cage 81 in which one or more persons may stand. Said cage 81 has a rectangular floor or platform 82 from the corners of which extend upwardly, outer corner posts 83 and inner corner posts 84 interconnected by side rails 85 disposed above

the floor, and by top sails or bars 86a. The posts 83, 84 on one side are connected to those on the other side by an outer bar 86 and an inner bar 87. The cage 81 also has a sub-floor 90. At its lower end, said cage has rollers 91 and, at its upper end, inwardly extending bars 92 carrying rollers 93.

At the upper end of the cage are upwardly and inwardly inclined braces 94 coming to a central apex above the cage carrying a pulley 95. A second pulley 96 is carried on a plate 97 fixed to the middle of bar 86, and is in alignment with pulley 95.

On the sub-floor 90 is a motor 100 connected by gearing 101 to a winch 102 from which extends a cable 103 passing up over pulley 96 and under pulley 95. The upper end of cable 103 is connected as at 110 to tongue 36 at the rear end of the lowermost ladder 25.

Rollers 91 and 93 are of the swivel type to permit travel vertically or horizontally.

Bars 92 are of such length as to maintain the floor or platform of the cage in a reasonably horizontal position over the entire vertical travel of the hanging scaffold.

A protective vertical rectangular channel shaped screen 111 may be attached to a cross bar 112, the ends of which are fixed to posts 84. Also, plate 97 may be supported by inclined braces 115 fixed at their lower ends to posts 83. The cable 103 passes up through channel screen 111.

An operator may stand on floor 82 when the cage 81 is in its down position. The motor 100 may then be energized to wind cable on the winch 102 to cause the cage to be drawn up. From the cage, the operator can climb onto the lowermost ladder and then make his way up to any of the ladders. Also, the operator can step off the upmost ladder onto the upper, almost flat surface of the dome structure. When it is desired to move the scaffolding sideways, the motors 60 are energized.

The anchor bearing 14 will now be described. Said anchor bearing comprises a vertical axial post or tube 150 (FIG. 11) welded to the axial top of the dome 10 and extends up therefrom. Disposed concentrically about the lower end of the tube 150 and spaced therefrom, is an outer tube 151 formed with a top outwardly extending flange 152 and with outwardly extending, vertical, radial ribs 153. Set-screws 154 screwed radially through outer tube 151 engage inner tube 150 to hold the outer tube against movement.

Above lower outer tube 151 is an upper outer tube 156 telescoped over inner tube 150 but spaced concentrically therefrom. At the lower end of tube 156 is an outwardly extending flange 157 disposed above flange 152. Between flanges 152, 157 is a thrust ball bearing 158. Tubes 151 and 156 are preferably of similar diameter.

Said upper, outer tube 156 is formed at each of different levels thereof, with more than two arcuate slots 160, and with pairs of outer apertured ears 161 at opposite sides of said slot and supporting rollers 162 projecting through said slots and engaging the inner fixed tube 150. Tube 156 is thus mounted for axial rotation about fixed tube 150.

Fixed to opposite sides of tube 156 are apertured ears 163 receiving shackles 164 to which the cables 16 are connected as at 165.

A two part split clamp 170 comprising two substantially semi-cylindrical parts 171 bolted together, as by bolts 172, is clamped to the upper end of tube 150 above tube 156. The motorized winch 15 may be mounted on a plate 175 supported on the fingers of upstanding brackets 176 integrally formed with tube 156 and extending above clamp 170.

The winch 15 may first be used to pull the cables 16, dollies 17 and ladders 25 up to desired position. Then the winch cable may be disconnected from the cables 16. The cables 16 are then connected by shackles 164 to the ears 161.

The winch 15 may then be used to suspend a free safety top, if desired.

It will be noted that as the ladders move around the dome, the tube 156 may rotate slowly about fixed tube 150.

The winch 15 may of course also be used to lower the ladders.

It will thus be seen that there is provided an apparatus in which the several objects of this invention are achieved and which is well adapted to meet the conditions of practical use.

As possible embodiments might be made of the above invention, and as various changes might be made in the embodiment above set forth, it is to be understood that all matter herein set forth or shown in the accompanying drawings is to be interpreted as illustrative and not in a limiting sense.

I claim:

1. In combination, a domed structure, an anchor at the top of the structure, scaffolding comprising a plurality of scaffold ladders provided with steps and located on the outside of the structure, means to connect said ladders in tandem, said anchor comprising a member rotatable about the vertical axis of the domed structure, cable means connecting the uppermost of said ladders to said rotatable member, dolly means connected to said cable means and engaging the outer surface of the domed structure, motive means on the scaffolding and engaging the outer surface of the domed structure for moving the scaffolding about the vertical axis of the domed structure, a hanging scaffold, and means suspending said hanging scaffold from the lowermost ladder, said last named means including means for raising and lowering the hanging scaffold relative to said lowermost ladder.

2. In combination, a domed structure having an anchor at its top, scaffolding extending outwardly and downwardly over the surface of said domed structure and connected to said anchor for movement around the domed structure, said scaffolding comprising a plurality of rigid ladders and means releasably interconnecting them in tandem, and means for rotating the scaffolding about the axis of the domed structure, said means comprising rollers carried by said ladders and engaging the surface of the domed structure, each of said rollers being mounted on its associated ladder for rotation about an axis lying in a generally vertical plane and generally parallel to the surface of the domed structure, and power-operated means carried by each ladder and operatively connected to the roller thereof for driving the roller, the several power-operated means being so coordinated with respect to their speeds of operation that the several ladders will remain in at least approximate alignment as the scaffolding rotates about the axis of the domed structure as a result of power-effected rotation of said rollers about their respective axes.

3. The combination of claim 2 with the addition that said scaffolding is connected to said anchor through suspending means extending between the anchor and the uppermost ladder, said suspending means being adjustable in effective length to vary the distance of the scaffolding from the axis of the domed structure, each of said ladders being provided adjacent said roller with a

second roller adapted to provide rolling support for the ladder from the domed structure when the scaffolding moves toward or away from the axis of the domed structure as a result of varying the length of said suspending means, and means for adjusting one of said rollers relative to the other along a line perpendicular to the surface of the domed structure whereby either roller can be brought into, and the other roller out of, engagement with the domed structure to adapt the ladder for movement alternatively about or toward and away from the axis of the domed structure.

4. The combination of claim 3 with the addition that said rollers are located near one end of the ladder, and one or more casters supporting the other end of the ladder from the domed structure.

5. The combination of claim 2 with the addition of a hanging scaffold and means for suspending said hanging scaffold from the lowermost of said ladders, said suspending means being adjustable to vary the height of said hanging scaffold.

6. In combination, a domed structure having an anchor at its top, elongated scaffolding extending outwardly and downwardly over the surface of said domed structure, means extending between the upper, inner end of said scaffolding and said anchor for limiting outward and downward movement of the scaffolding under the influence of gravity, said means being adjustable in effective length to vary the distance between the scaffolding and the axis of the domed structure, wheeled casters mounted at spaced intervals along said scaffolding for supporting the scaffolding from the surface of the domed structure, each of said casters being swiveled on the scaffolding on an axis perpendicular to the surface of the domed structure and movable about such axis to permit the caster to be disposed either in a first position with the axis of its wheel extending parallel to the scaffolding or in a second position with the axis of its wheel extending transverse to the scaffolding, and motive means for swinging the scaffolding about the axis of the domed structure.

7. The combination of claim 6 with the addition that said scaffolding comprises a series of flexibly interconnected ladders, a plurality of said casters being mounted on each of said ladders.

8. The combination of claim 6 with the addition of releasable means for locking each caster in either of said positions.
